(57) **CLAIM**

The ornamental design for a bracket, as shown and described.

DESCRIPTION

FIG. 1 is a front perspective view of an embodiment of the bracket;

FIG. 2 is a rear perspective view of the bracket of FIG. 1; FIG. 3 is a top view of the bracket of FIG. 1, with the bottom view being a mirror image;

FIG. 4 is a left side view of the bracket of FIG. 1;

FIG. 5 is a right side view of the bracket of FIG. 1;

FIG. 6 is a front view of the bracket of FIG. 1, with the rear view being a mirror image; and,

FIG. 7 is an in-use view of the bracket of FIG. 1.

The broken lines depict portions of the article and environment that form no part of the claimed design.

1 Claim, 7 Drawing Sheets
